ELECTRO-MECHANICAL INTERLOCK

Hibberd R. Crispen and Charles N. Fendrich, Harrisburg, Pa., assignors to Inclinator Company of America, Harrisburg, Pa., a company of Pennsylvania
Filed Dec. 7, 1964, Ser. No. 416,334
12 Claims. (Cl. 187—31)

The present invention relates to an electro-mechanical interlock mechanism. More specifically, the present invention relates to an electro-mechanical interlock mechanism for hoistway doors of elevators.

In elevator installations, it is customary to prevent the operation of the elevator car unless the hoistway doors at all floors are closed. Thus, the elevator car cannot be moved away from a given floor until the hoistway door at that floor is closed. This is generally accomplished by an interlock mechanism in which an electrical switch is held in an open position to prevent completion of the operating circuit of the elevator car until the hoistway door is completely closed and mechanically locked. However, because of the inordinate expense and impracticality of operating both the door lock and the elevator switch at exactly the same instant, there is always the possibility that a door will be left open a short distance by accident and the elevator car will still operate with this dangerous condition in existence.

It is therefore an object of the present invention to provide an improved interlock mechanism for doors in which opening of the door a short distance will interrupt the circuit operating another mechanism.

A further object of the present invention is to provide an improved interlock mechanism for elevator doors in which opening of the door a short distance will interrupt the circuit operating the elevator car.

Another object of the present invention is to provide an interlock mechanism for elevator doors in which opening the door a small amount will interrupt the circuit operating the elevator car but the door will be prevented from opening more than a predetermined distance from the jamb.

A further object of the present invention is to provide an improved interlock mechanism for elevator doors in which a door left part-way open will interrupt the circuit operating the elevator car while open, but a return mechanism will completely close the door thereby re-completing the circuit.

Still another object of the present invention is to provide an improved interlock mechanism for elevator doors in which the circuit operating the elevator car is interrupted if the latch mechanism of the hoistway door is not locked internally.

In accordance with the present invention, the above objectives are accomplished by providing a three-position latch mechanism for a hoistway door. In a first position, representing the completely closed position of the door, the circuit operating the elevator car is closed and the hoistway door is held in its completely closed position by a spring mechanism. In the second position, the door is a predetermined distance from the jamb, but is mechanically blocked from opening any further, the circuit operating the elevator car is open and the latch mechanism is under spring tension tending pull the door completely closed. In its third position, the door is open, the circuit operating the elevator car is open and the latch mechanism has passed through a center position and is held in its completely open position.

The above objects and advantages of the present invention will be apparent from the following detailed description, when read in conjunction with the drawings, wherein:

FIGURE 1 is a plan view, partially in section, of the interlock mechanism;

2

FIGURE 2 is a side elevational view, partially in section, of the interlock mechanism;

FIGURES 3a, b and c, partially in section, show the three basic positions of the latch mechanism; and

FIGURES 4a, b and c show the three basic positions of the electrical switching circuit.

In the drawings, the numeral 10 designates a base plate vertically mounted on the door jamb 12, of an elevator hoistway opening. Mounted on the hoistway door 14 is lock bar 16. Lock bar 16 has formed therein, adjacent its upper edge and on its free end, a rectangular slot 18. Mounted near the lower end of plate 10 is terminal block 20 having terminals 22, 24 and 26 mounted thereon. Also mounted on plate 10 above terminal block 20 is snap action switch 28, having contact button 30 spring biased in its extended position. Attached to plate 10 through switch 28 is mounting plate 32. Attached to the rearward side of plate 32 is snap action switch 34. Switch 34 has contact button 36 normally biased in its extended position. Also pivotally attached to switch 34 on pivot 38 is operating arm 40, which is adapted to press against and operate contact button 36. Mounted on the free end of operating arm 40 is roller 42. Roller element 42 is adapted to cooperate with and act as a follower for generally circular cam member 44. Cam member 44 is pivotally mounted on plate 10 through pivot element 46. It is to be noted that when roller element 42 is riding on the circular portion 48 of cam member 44, contact button 36 is depressed, while, when roller element 42 is adjacent straight section 50 of cam member 44, contact button 36 is released and in its extended position. Mounted adjacent the peripheral edge of cam member 44 and protruding therefrom are cylindrical lock pins 52 and 54, respectively. Lock pin 52 fits within slot 18 when cam 44 is in the first and second positions shown in FIGURES 3a and 3b, but is free of slot 18 when cam member 44 is in the position shown in FIGURE 3c. Attached to the free end of lock pin 54 is one end of helical spring 56. The other end of spring 56 is attached to mounting block 58, which, in turn, is attached to plate 10. It is to be noted that spring 56 is under tension and holds cam member 44 in the position shown in FIGURE 3a when the door is completely closed. When the door is opened a predetermined distance, latch pin 54 moves to a point just short of the center position, as shown in FIGURE 3b, in which position spring 56 is further stretched and therefore tends to return cam 44 to the position shown in FIGURE 3a. However, if cam member 44 is turned still further to cause pin 54 to pass through the center position, spring 56 will tend to continue to rotate cam 44 to the position shown in FIGURE 3c and hold it in that position. Stop 60 on the peripheral edge of cam 44 limits the movement of cam 44 in a clockwise direction, while stop 62 limits the movement of cam 44 in a counter-clockwise direction. Accordingly, cam 44 moves through a preselected arc, from one extreme position, counter-clockwise through a center position and thence to a second extreme position. In accordance with the present invention, this movement is confined to an arc representing approximately 80°. Also formed in the upper portion of the peripheral edge of cam 44 is arcuate slot 64. Slot 64 cooperates with movable cylindrical pin 66. When cylindrical pin 66 is in its lowermost position and cam 44 is in the position shown in FIGURE 3a, pin 66 abuts shoulder 68 of slot 64 and when cam 44 has passed through an arc sufficient to have pin 54 just short of its center position, pin 66 abuts shoulder 70 of slot 64. Thus, it is clear that, when pin 66 is in its lowermost position, pin 66 permits a limited arcuate movement of cam 44 to a position whereby pin 54 is just short of its center position and cam 44 is being urged back to its original position of FIGURE 3a by spring 56. Also mounted on block 58 is snap action switch 72. Switch 72 has contact button 74, normally

biased in its extended position, which is operated by operating arm 76 pivotally connected to switch 72 through pivot 78. Operating arm 76 is in contact with collar 80 mounted in a fixed position on pin 66. When pin 66 is in its lowermost position, operating arm 76 depresses contact button 74, and when pin 66 is raised, contact button 74 is released to its extended position. Connected to the upper end of pin 66, by means of manual pin lifting element 82, is solenoid core 84. Solenoid core 84 is surrounded by coil 86 which, when energized, is adapted to draw core 84 upwardly a distance sufficient for pin 66 to clear the outer periphery of cam 44 and to remove the pressure of collar 80 from operating arm 76, thereby releasing the contact button 74. Coil 86 and core 84 make up a 24-volt solenoid 88 which is mounted on plate 10 adjacent its upper end.

To facilitate the description of the operation of the interlock mechanism of the present invention, FIGURES 3a, b and c have been included to show the three basic positions of the latch mechanism. FIGURES 4a, b and c have also been included to show the positions of the switches of the electrical system, when the latch mechanism is in the position shown in drawings 3a, b and c, respectively. Accordingly, in the following detailed description of the operation of the electro-mechanical interlock mechanism of the present invention, drawings 3a, 3b, 3c, 4a, 4b and 4c will be referred to in conjunction with FIGURES 1 and 2.

Referring first to FIGURES 3a and 4a, it is to be observed that FIGURE 3a shows the latch mechanism in exactly the same position as it is shown in FIGURE 1. The door in FIGURE 3a is completely closed. It is to be observed that, with the latch mechanism in the position shown, spring 56 will hold cam 44 in the furthermost clockwise position permitted by stop 60. The position of cam 44 causes the pin 52 to press against the bottom and left side of slot 18 of lock bar 16, thereby holding door 14 in its closed position. Pin 66 is in its lowermost position riding in arcuate slot 64, since, as will be pointed out hereinafter, solenoid 88 is not energized. Finally, roller 42, attached to switch 34 through operating arm 40, is in contact with the peripheral edge 48 of cam 44. As shown in FIGURE 4a, switch 34 is normally biased in its open position, and when roller 42 is riding the peripheral edge 48 of cam 44 the button 36 of switch 34 is depressed, thereby holding switch 34 in its closed position. When pin 66 is in its lowermost position, button 74 of switch 72 is depressed by collar 80 through operating arm 76. Switch 72 is normally biased in its open position and therefore the depression of button 74 closes switch 72. With door 14 completely closed, button 30 of switch 28 will be depressed. Switch 28 is normally biased against contacts 90 and, therefore, when button 30 is depressed, switch 28 will be depressed against contacts 92, thereby bridging these contacts. Electrical line 94 is a live lead from a 24-volt source of electrical current and, as shown, is connected to terminal 22 of the electro-mechanical interlock system, of each floor served by the elevator, through electrical line 96. Mounted in line 96 is rail switch 98, which is normally biased in its open position. For simplicity of illustration, switch 98 is shown as a snap action switch but it may take other forms. Rail switch 98 is tripped and closed when the elevator car reaches the floor in question. Electrical line 100 also originates at the source of energy but comes from the right hand terminal, for example, terminal 26 of FIGURE 4a, of the previous interlock mechanism if there is such an interlock interposed between the source of energy and the interlock mechanism shown. In like fashion, electrical line 102, from terminal 26 of the interlock mechanism shown, passes to a terminal, such as, terminal 24 of the next succeeding interlock mechanism or to a floating cord if no succeeding interlock mechanism exists. In any event, 24 volts of electrical energy are impressed across lines 94 and 100. By observing FIGURE 4a, with the switches 34, 72 and 28 in the positions shown, it is to

be seen that, when the door is completely closed, coil 86 is de-energized due to the fact that switch 28 is bridging contacts 92 and contacts 90 are open. However, electrical energy is being supplied to the next succeeding interlock mechanism through line 94 and line 100 through contact 22, switch 28, switch 72, contact 26 and electrical line 102. It should also be noted that this condition persists so long as the door is closed, irrespective of whether the elevator is at the floor in question and rail switch 98 is closed or rail switch 98 is open as shown.

The next basic position of the latch system is shown in FIGURE 3b. In FIGURE 3b door 14 has been opened just far enough (about $\frac{1}{4}$ of an inch) to release button 30 of switch 28. Pin 66 has passed along arcuate slot 64 until it is just about to touch shoulder 70 of slot 64. Roller 42 is still riding on circular periphery 48 of cam 44 and is just about to leave this circular surface to ride along straight surface 50 on the periphery of cam 44. In the position shown, pin 66 abutting against shoulder 70 prevents cam 44 from turning any further. Also, since pin 66 still rides in slot 64, collar 80 will still hold switch 72 closed. Pin 52 is still in slot 18 of lock bar 16. Thus, the door cannot be opened any further because of the blocking action of pin 66 and pin 52. In addition, the door 14, when in this position, must be held open by the person attempting to open the door, due to the fact that spring 56 is extended further than it was in FIGURE 3a and cam 44 is being urged in a clockwise direction, thereby pulling lock bar 16 inwardly through pin 52 and door 14 to the closed position. Referring now to FIGURE 4b, the electrical switch system is in the condition recited below. First of all, since roller 42 is still on circular periphery 48 of cam 44, switch 34 is still depressed thereby maintaining switch 34 in its closed position. However, the opening of the door and the release of button 30 has caused switch 28 to be released and bridge contacts 90. If we now assume that the elevator car has not reached the floor in question and switch 98 is still open, the circuit through coil 86 is still not made and pin 66 remains in its lowermost position; but, except for the fact that rail switch 98 is still held open, the circuit would be complete through coil 86. Switch 72 is also still depressed and therefore closed, since pin 66 is still in its lowermost position, but no current can flow in control circuit 102 to the next succeeding interlock because contacts 92 of switch 28 are open. Stated differently, the circuit through coil 86 will remain open so long as the door is closed or the elevator car is not at the floor in question, and, so long as the elevator car is not at the floor in question the door cannot be opened further and, in fact, spring 56 will pull it completely shut.

Now assume that the elevator car is at the floor in question and switch 98 is closed, as shown in FIGURE 4b. The circuit through coil 86 is now complete and coil 86 is energized pulling core 84 into coil 86 and, by the same action, lifting pin 66 out of slot 64. The lifting of pin 66 frees cam 44 to rotate further in a counterclockwise direction. By the same token, lock bar 16 is free to move outwardly away from the interlock mechanism and the door 14 is free to open. Opening door 14 a slight bit further will rotate cam 44 counterclockwise and cause roller 42 to leave circular periphery 48 of cam 44 and enter upon straight surface 50 of the periphery of cam 44.

FIGURE 3c shows the latch mechanism with the door 14 open still further or, in essence, in its completely open position. In this completely open position a number of changes take place. As previously indicated, roller 42 is now riding surface 50 of cam 44, rather than surface 48. In addition, pin 66 has been lifted from slot 64 and is riding circular periphery 48 of cam 44. Pin 54 has passed to the right of the center line through the point of pivot of cam 44 and the spring 56 will then continue to pull cam 44 in a counterclockwise direction

until stop 62 strikes mounting block 58 and stops this rotation. Finally, pin 52 has moved out of slot 18 of lock bar 16, thereby completely releasing lock bar 16 and door 14. The door may then be opened completely and will not be reclosed by the latch mechanism. As shown in FIGURE 4c, when the door is completely open, roller 42 is riding straight surface 50 of cam 44 and has therefore permitted operating arm 40 to move upwardly and to the right and release button 36 of switch 34. Since switch 34 is normally biased in its open position, the biasing spring will open switch 34 as shown. Since pin 66 has been raised, this pin, in turn, has raised collar 80 and permitted operating arm 76 to raise and release button 74 of switch 72. Since switch 72 is normally biased in its open position, the release of button 74 will open switch 72. Since the door is open, it is not pressing against button 30 of switch 28 and, therefore, this button is released. Since switch 28 is normally biased against contacts 90, the release of button 30 will cause switch 28 to remain in the position where it bridges contacts 90. Also, since the elevator is at the floor in question, switch 98, which is normally biased in an open position, will be held closed by the elevator car. Thus both the circuit through the coil of the interlock on the floor in question is open because of open switch 34 and the circuit to the next succeeding interlock mechanism is open, since switch 72 is also in its open position, and switch 28 has also opened contacts 92. This condition persists so long as the door is open. Further, accidental pushing of button 30, thereby closing contacts 92, will not alter the situation.

FIGURES 3c and 4c also show the condition just prior to closing door 14 and reversing the previously described sequence of steps. Specifically, when door 14 is closed, lock bar 16 contacts pin 54, as shown in FIGURE 3c, and further closing will cause lock bar 16 to push against pin 54 and rotate cam 44 in a clockwise direction overcoming the tension of spring 56. The rotation of cam 44 in a clockwise direction causes pin 54 to pass the center line through pivot of cam 44. At the same time, pin 52 again begins to enter slot 18 of lock bar 16. When pin 54 passes the center line of cam 44, the spring 56 again takes over and urges cam 44 in a clockwise direction as far as possible, that is, until stop 60 contacts mounting block 58. This continued clockwise rotation of cam 44 causes pin 52, which is now in slot 88, to pull lock bar 16 and door 14 to the completely closed position, as previously shown and described in FIGURES 3a and 4a. The switches 34, 72 and 28 will return to the positions shown in FIGURE 4a and when the elevator car leaves the floor in question, switch 98 will open.

It is to be understood that the present invention may be utilized with equal facility on a door which is hinged from the side of an opening, as was assumed in the present description, or on a sliding door; and, while an interlock for a "left hand" door is shown, right hand models can obviously be made. In addition, other variations and modifications will be obvious to one skilled in the art. For example, the circuit supplying energy to the elevator car can be made to include contacts 92 of switch 28 so that the car will not move when a hoistway door is open, as in FIGURES 3c and 4c, or is ajar, as in FIGURES 3b and 4b; or it can include switch 72 so that the car will not move when the door has been opened beyond the point illustrated by FIGURE 3b. Therefore, the present invention is to be limited only in accordance with the appended claims.

We claim:

1. An electro-mechanical interlock mechanism for elevator hoistway doors comprising:
  - (a) a generally rectangular base plate attached to the door jamb of the hoistway opening in a vertical manner;

- (b) a generally disc-shaped cam member rotatably mounted on said base plate near the center thereof;
- (c) support block means rigidly attached to said base plate above said cam and in the immediate vicinity thereof;
- (d) two stops radially protruding from the edge of said cam and adapted to cooperatively engage said block, a first of said stops engaging said block at a first rotational position of said cam and the second of said stops engaging said block at a second rotational position of said cam about 80° of rotation from said first position;
- (e) a first cylindrical pin means mounted on said cam and having its axis perpendicular to the face of said cam and its circumferential edge coinciding with the circumferential edge of said cam and positioned on said cam such that it will be on one side of a vertical plane passing through the axis of rotation of said cam when said cam is in its said first rotational position and on the other side of said plane when said cam is in its second rotational position;
- (f) second cylindrical pin means mounted on said cam and having its axis perpendicular to the face of said cam and its circumferential edge coinciding with the circumferential edge of said cam and positioned on said cam such that its axis coincides with said vertical plane when said cam is in its rotational position and more than about 30° of rotation from said vertical plane and on the same side of said vertical plane as said first pin, when said cam is in its second position of rotation;
- (g) helical spring means having one end attached to said first pin and its other end connected to said block on the side of said vertical plane to which said first pin rotates when said cam is in its second rotational position;
- (h) said cam having a sector-shaped slot formed in its edge beginning at a point adjacent said first stop and extending slightly more than about 30° of rotation toward said second stop;
- (i) third pin means having its central axis in alignment with said vertical plane and slideably passing through said block for limited vertical movement into contact with the upper edge of said cam in a manner such that said third pin will limit the rotation of said cam to about 30° of rotation, when it is in its downward position and in said sector-shaped slot, and will contact the outermost peripheral edge of said cam when it is in its uppermost position and said cam is approaching said second rotational position;
- (j) a solenoid mounted on said base plate adjacent its upper end and having a movable cylindrical core whose central axis is in alignment with the axis of said third pin;
- (k) manually operable lift means holding said core and said third pin rigidly together and adapted to move said third pin between its lowermost and its uppermost position;
- (l) first switch means, normally biased in its open position, mounted on said support block;
- (m) collar means rigidly mounted about said third pin means above said support block;
- (n) arm means pivotally mounted on said first switch and having its free end in contact with the lower edge of said collar, said arm being held outwardly by the biasing force of said switch when said third pin is in its most uppermost position and being forced inwardly to overcome the biasing force of said switch and close said switch when said third pin is in its lowermost position;
- (o) said cam also having a flat chord formed on its edge between said first stop and said first pin;
- (p) second switch means, normally biased in its open position, mounted below said cam;
- (q) follower means pivotally mounted on said second

switch and having its free end in contact with the edge of said cam, said follower being held outwardly by the biasing force of said switch when said cam is in its second position of rotation and said follower is in contact with the straight chord section of said cam and being forced inwardly to overcome the biasing force of said switch and close said switch when said cam is in its second rotational position and said follower is in contact with the circular section of said cam;

(r) third switch means mounted on said base plate below said cam and normally biased toward a first set of contacts to close said first contacts and normally biased away from a second set of contacts to hold said second contacts open until said biasing force is overcome;

(s) push button means connected to the biasing means of said third switch and extending beyond the edge of said base plate a distance such that completely closing said hoistway door will overcome the biasing force of said third switch and close said second contacts and opening said door will release the biasing force and close said first contacts;

(t) lock bar means mounted on said door and having a rectangular slot formed in its upper edge such that said slot will receive and hold said second pin when said door is completely closed and said cam is in its first rotational position and will free said second pin just prior to the point at which said cam is in its second rotational position;

(u) a source of electrical energy;

(v) fourth switch means which is closed by the elevator car when said car reaches the floor at which the interlock mechanism is located;

(w) a first electrical circuit serially connecting said source of energy to said fourth switch, said coil of said solenoid, said second switch, and said first contacts of third switch; and

(x) a second electrical circuit serially connecting said source of energy to said second contacts of said third switch, said first switch and an interlock mechanism located on another floor.

2. An electro-mechanical interlock mechanism for doors, comprising:

(a) latch means having one portion thereof mounted on a door and a second portion mounted on a wall forming the opening for said door;

(b) said first and second portions of said latch means being releasably coupled together until said door is opened a predetermined small distance and decoupled when said door is opened a distance greater than said predetermined distance;

(c) electrically-operated limiter means operatively associated with one of said portions of said latch means and adapted to prevent said latch means for coupling and said door for opening a distance greater than said predetermined distance when said limiter means is in a first condition of energization and to permit said latch means to decouple and said door to open a distance greater than said predetermined distance when said limiter means is in a second condition of energization;

(d) switch means responsive to a changing condition and adapted to alternately connect said limiter means to and disconnect said limiter means from a source of electrical energy in response to changes in said condition;

(e) spring means operatively connected to that portion of said latch means with which said limiter means is associated and adapted to apply tension to said latch means and pull said door to a completely closed position when said door is opened a distance less than said predetermined distance and said limiter means

is in a position to prevent said latch means from decoupling.

3. An electro-mechanical interlock mechanism for doors, comprising:

(a) latch means having one portion thereof mounted on a door and a second portion mounted on a wall forming the opening for said door;

(b) said first and second portions of said latch means being releasably coupled together until said door is opened a predetermined small distance and decoupled when said door is opened a distance greater than said predetermined distance;

(c) electrically-operated limiter means operatively associated with one of said portions of said latch means and adapted to prevent said latch means for decoupling and said door from opening a distance greater than said predetermined distance when said limiter means is in a first condition of energization and to permit said latch means to decouple and said door to open a distance greater than said predetermined distance when said limiter means is in a second condition of energization;

(d) switch means responsive to a changing condition and adapted to alternately connect said limiter means to and disconnect said limiter means from a source of electrical energy in response to changes in said condition;

(e) spring means operatively connected to that portion of said latch means with which said limiter means is associated and adapted to apply tension to said latch means and pull said door to a completely closed position when said door is opened a distance less than said predetermined distance and said limiter means is in a position to prevent said latch means from decoupling, and to apply tension to said latch means to hold said latch means in its decoupled position when said limiter means is in a position to permit said latch means to decouple.

4. An electro-mechanical interlock mechanism for doors, comprising:

(a) latch means having one portion thereof mounted on a door and a second portion mounted on a wall forming the opening for said door;

(b) said first and second portions of said latch means being releasably coupled together until said door is opened a predetermined small distance and decoupled when said door is opened a distance greater than said predetermined distance;

(c) electrically-operated limiter means operatively associated with one of said portions of said latch means and adapted to prevent said latch means from decoupling and said door for opening a distance greater than said predetermined distance when said limiter means is in a first condition of energization and to permit said latch means to decouple and said door to open a distance greater than said predetermined distance when said limiter means is in a second condition of energization;

(d) first switch means responsive to a changing condition and adapted to alternately connect said limiter means to and disconnect said limiter means from a source of electrical energy in response to changes in said condition;

(e) second switch means adjacent to and operated by said limiter means and adapted to alternately connect said source of electrical energy to a remotely located mechanism when said limiter means is in a position to prevent said latch means from decoupling and disconnect said source of electrical energy from said remotely located mechanism when said limiter means is in a position to permit said latch means to decouple.

5. An electro-mechanical interlock mechanism for doors, comprising:

(a) latch means having one portion thereof mounted

- on a door and a second portion mounted on a wall forming the opening for said door;
- (b) said first and second portions of said latch means being releasably coupled together until said door is opened a predetermined small distance and decoupled when said door is opened a distance greater than said predetermined distance;
- (c) electrically-operated limiter means operatively associated with one of said portions of said latch means and adapted to prevent said latch means from decoupling and said door from opening a distance greater than said predetermined distance when said limiter means is in a first condition of energization and to permit said latch means to decouple and said door to open a distance greater than said predetermined distance when said limiter means is in a second condition of energization;
- (d) first switch means responsive to a changing condition and adapted to alternately connect said limiter means to and disconnect said limiter means from a source of electrical energy in response to changes in said condition;
- (e) second switch means adjacent to and operated by said door and adapted to alternately connect said source of electrical energy to said limiter means when said door is open, and disconnect said source of electrical energy from said limiter means when said door is closed; and
- (f) third switch means adjacent to and operated by said limiter means and adapted to alternately connect said source of electrical energy to a remotely located mechanism when said limiter means is in a position to prevent said latch means from decoupling and disconnect said source of electrical energy from said remotely located mechanism when said limiter means is in a position to permit said latch means to decouple.
6. An electro-mechanical interlock mechanism for doors, comprising:
- (a) latch means having one portion thereof mounted on a door and a second portion mounted on a wall forming the opening for said door;
- (b) said first and second portions of said latch means being releasably coupled together until said door is opened a predetermined small distance and decoupled when said door is opened a distance greater than said predetermined distance;
- (c) electrically-operated limited means operatively associated with one of said portions of said latch means and adapted to prevent said latch means from decoupling and said door from opening a distance greater than said predetermined distance when said limited means is in a first condition of energization and to permit said latch means to decouple and said door to open a distance greater than said predetermined distance when said limiter means is in a second condition of energization;
- (d) first switch means responsive to a changing condition and adapted to alternately connect said limiter means to and disconnect said limiter means from a source of electrical energy in response to changes in said condition;
- (e) second switch means adjacent to and operated by that portion of said latch means with which said limiter means is associated and adapted to alternately connect said source of electrical energy to said limiter means when said door is closed and while said door is open less than said predetermined distance and disconnect said source of electrical energy from said limiter means when said door is opened a distance greater than said predetermined distance.
7. An electro-mechanical interlock mechanism for doors, comprising:
- (a) latch means having one portion thereof mounted on a door and a second portion mounted on a wall forming the opening for said door;
- (b) said first and second portions of said latch means

- being releaseably coupled together until said door is opened a predetermined small distance and decoupled when said door is opened a distance greater than said predetermined distance;
- (c) electrically-operated limiter means operatively associated with one of said portions of said latch means and adapted to prevent said latch means from decoupling and said door from opening a distance greater than said predetermined distance when said limiter means is in a first condition of energization and to permit said latch means to decouple and said door to open a distance greater than said predetermined distance when said limiter means is in a second condition of energization;
- (d) first switch means responsive to a changing condition and adapted to alternately connect said limiter means to and disconnect said limiter means from a source of electrical energy in response to changes in said condition;
- (e) second switch means adjacent to and operated by said door and adapted to alternately connect said source of electrical energy to said limiter means when said door is open, and disconnect said source of electrical energy from said limiter means when said door is closed; and
- (f) third switch means adjacent to and operated by said limiter means and adapted to alternately connect said source of electrical energy to a remotely located mechanism when said limiter means is in a position to prevent said latch means from decoupling and disconnect said source of electrical energy from said remotely located mechanism when said limiter means is in a position to permit said latch means to decouple;
- (g) fourth switch means adjacent to and operated by that portion of said latch means with said limiter means is associated and adapted to alternately connect said source of electrical energy to said limiter means until said door is opened said predetermined distance and disconnect said source of electrical energy from said limiter means when said door is opened a distance greater than said predetermined distance.
8. An electro-mechanical interlock mechanism for doors, comprising:
- (a) latch means having one portion thereof mounted on a door and a second portion mounted on a wall forming the opening for said door;
- (b) said first and second portions of said latch means being releasably coupled together until said door is opened a predetermined small distance and decoupled when said door is opened a distance greater than said predetermined distance;
- (c) electrically-operated limiter means operatively associated with one of said portions of said latch means and adapted to prevent said latch means from decoupling and said door from opening a distance greater than said predetermined distance when said limiter means is in a first condition of energization and to permit said latch means to decouple and said door to open a distance greater than said predetermined distance when said limiter means is in a second condition of energization;
- (d) first switch means responsive to a changing condition and adapted to alternately connect said limiter means to and disconnect said limiter means from a source of electrical energy in response to changes in said condition;
- (e) second switch means adjacent to and operated by said door and adapted to alternately connect said source of electrical energy to said limiter means when said door is open, and disconnect said source of energy from said limiter means when said door is closed;
- (f) spring means operatively connected to that portion of said latch means with which said limiter means is

associated and adapted to apply tension to said latch means and pull said door to a completely closed position when said door is opened a distance less than said predetermined distance and said limiter means is in a position to prevent said latch means from 5 decoupling.

9. An electro-mechanical interlock mechanism for doors, comprising:

- (a) latch means having one portion thereof mounted on a door and a second portion mounted on a wall 10 forming the opening for said door;
- (b) said first and second portions of said latch means being releasably coupled together until said door is opened a predetermined small distance and decoupled when said door is opened a distance greater 15 than said predetermined distance;
- (c) electrically-operated limiter means operatively associated with one of said portions of said latch means and adapted to prevent said latch means from decoupling and said door from opening a distance 20 greater than said predetermined distance when said limiter means is in a first condition of energization and to permit said latch means to decouple and said door to open a distance greater than said predetermined distance when said limiter means is in a second 25 condition of energization;
- (d) first switch means responsive to a changing condition and adapted to alternately connect said limiter means to and disconnect said limiter means from a source of electrical energy in response to changes in 30 said condition;
- (e) second switch means adjacent to and operated by said door and adapted to alternately connect said source of electrical energy to said limiter means when said door is open, and disconnect said source of 35 energy from said limiter means when said door is closed;
- (f) spring means operatively connected to that portion of said latch means with which said limiter means is associated and adapted to apply tension to 40 said latch means and pull said door to a completely closed position when said door is opened a distance less than said predetermined distance and said limiter means is in a position to prevent said latch means from decoupling and to apply tension to said latch means to hold said latch means in its decoupled 45 position when said limiter means is in a position to permit said latch means to decouple.

10. An electro-mechanical interlock mechanism for doors, comprising:

- (a) latch means having one portion thereof mounted 50 on a door and a second portion mounted on a wall forming the opening for said door;
- (b) said latch means; including a rotatable cam, forming one of said portions, releasably coupled to a lock bar element, forming the other of said 55 portions, until said door is opened a predetermined small distance and decoupled when said door is opened a distance greater than said predetermined distance;
- (c) electrically-operated limiter means operatively associated with said cam of said latch means and adapted to prevent said latch means from decoupling and said door from opening a distance greater than said predetermined distance when said limiter means is in a first condition of energization and to permit 60 said latch means to decouple and said door to open a distance greater than said predetermined distance when said limiter means is in a second condition of energization;
- (d) first switch means responsive to a changing condition and adapted to alternately connect said limiter means to and disconnect said limiter means from a source of electrical energy in response to changes in 65 said condition;
- (e) second switch means adjacent to and operated by 70

said door and adapted to alternately connect said source of electrical energy to said limiter means when said door is open, and disconnect said source of electrical energy from said limiter means when said door is closed; and

(f) third switch means adjacent to and operated by limiter means and adapted to alternately connect said source of electrical energy to a remotely located mechanism when said limiter means is in a position to prevent said latch means from decoupling and disconnect said source of electrical energy from said remotely located mechanism when said limiter means is in a position to permit said latch means to decouple;

(g) fourth switch means adjacent to and operated by that portion of said latch means with which said limiter means is associated and adapted to alternately connect said source of electrical energy to said limiter means until said door is opened said predetermined distance and disconnect said source of electrical energy from said limiter means when said door is opened a distance greater than said predetermined distance.

11. An electro-mechanical interlock mechanism for doors, comprising:

- (a) latch means having one portion thereof mounted on a door and a second portion mounted on a wall forming the opening for said door;
- (b) said first and second portions of said latch means being releasably coupled together until said door is opened a predetermined small distance and decoupled when said door is opened a distance greater than said predetermined distance;
- (c) a movable core electromagnet operatively associated with one of said portions of said latch means and adapted to prevent said latch means from decoupling, and said door from opening a distance greater than said predetermined distance when said movable core electromagnet is in a first condition of energization, and to permit said latch means to decouple and said door to open a distance greater than said predetermined distance when said movable core electromagnet is in a second condition of energization;
- (d) first switch means responsive to a changing condition and adapted to alternately connect said electromagnet to and disconnect said electromagnet from a source of electrical energy in response to changes in said condition;

(e) second switch means adjacent to and operated by said door and adapted to alternately connect said source of electrical energy to said electromagnet when said door is open, and disconnect said source of electrical energy from said electromagnet when said door is closed; and

(f) third switch means adjacent to and operated by said electromagnet and adapted to alternately connect said source of electrical energy to a remotely located mechanism when said electromagnet is in a position to prevent said latch means from decoupling and disconnect said source of electrical energy from said remotely located mechanism when said electromagnet is in a position to permit said latch means to decouple;

(g) fourth switch means adjacent to and operated by that portion of said latch means with which said electromagnet is associated and adapted to alternately connect said source of electrical energy to said electromagnet until said door is opened said predetermined distance and disconnect said source of electrical energy from said electromagnet when said door is opened a distance greater than said predetermined distance.

12. An electro-mechanical interlock mechanism for doors, comprising:

- (a) latch means having one portion thereof mounted

13

- on a door and a second portion mounted on a wall forming the opening for said door;
- (b) said latch means; including, a rotatable cam, forming one of said portions, releasably coupled to a lock bar element, forming the other of said portions, 5 until said door is opened a predetermined small distance and decoupled when said door is opened a distance greater than said predetermined distance;
- (c) a movable core electromagnet operatively associated with one of said portions of said latch means and 10 adapted to prevent said latch means from decoupling, and said door from opening a distance greater than said predetermined distance when said movable core electromagnet is in a first condition of energization, and to permit said latch means to decouple and said 15 door to open a distance greater than said predetermined distance when said movable core electromagnet is in a second condition of energization;
- (d) first switch means responsive to a changing condition and adapted to alternately connect said electromagnet to and disconnect said electromagnet from a source of electrical energy in response to changes in 20 said condition;
- (e) second switch means adjacent to and operated by said door and adapted to alternately connect said 25 source of electrical energy to said electromagnet when said door is open, and disconnect said source of

14

- electrical energy from said electromagnet when said door is closed; and
- (f) third switch means adjacent to and operated by said electromagnet and adapted to alternately connect said source of electrical energy to a remotely located mechanism when said electromagnet is in a position to prevent said latch means from decoupling and disconnect said source of electrical energy from said remotely located mechanism when said electromagnet is in a position to permit said latch means to decouple;
- (g) fourth switch means adjacent to and operated by said cam and adapted to alternately connect said source of electrical energy to said electromagnet until said door is opened said predetermined distance and disconnect said source of electrical energy from said electromagnet when said door is opened a distance greater than said predetermined distance.
